[57] **CLAIM**

The ornamental design for a handle for a plumbing fitting, as shown and described.

DESCRIPTION

FIG. 1 is a left, top, front perspective view of a handle for a plumbing fitting embodying our new design;

FIG. 2 is a front elevational view thereof, the rear elevational view being a mirror image of the front side shown;

FIG. 3 is a right side elevational view thereof;

FIG. 4 is a left side elevational view thereof;

FIG. 5 is a top plan view thereof;

FIG. 6 is a bottom plan view thereof;

FIG. 7 is a left, top, front perspective view of a second embodiment;

FIG. 8 is a front elevational view thereof, the rear elevational view being a mirror image of the front side shown;

FIG. 9 is a right side elevational view thereof;

FIG. 10 is a left side elevational view thereof;

FIG. 11 is a top plan view thereof; and,

FIG. 12 is a bottom plan view thereof.

The broken line representations of holes in FIGS. 6 and 12 are for purposes of illustration only, and form no part of the claimed design.
